UNITED STATES PATENT OFFICE.

LAZARD KAHN, OF HAMILTON, OHIO, ASSIGNOR TO F. & L. KAHN & BROS.,
OF SAME PLACE.

DESIGN FOR A STOVE DOOR OR PANEL.

SPECIFICATION forming part of Design No. 26,594, dated February 2, 1897.

Application filed October 28, 1896. Serial No. 610,377. Term of patent 14 years.

To all whom it may concern:

Be it known that I, LAZARD KAHN, a citizen of the United States, residing at Hamilton, Butler county, Ohio, have invented and produced a new and original Design for Stove Doors or Panels, of which the following is a specification, reference being had to the accompanying drawings, showing the same.

Figure 1 is a front elevation of the door or panel, showing my design; and Fig. 2 is a plan of the same, these two views being deemed necessary to fully illustrate my design.

The leading feature of my design consists of a substantially elliptical outline for the door or panel, in conjunction with a circular

closed front register projecting from the face thereof and having a handle.

A is the door or panel, which is substantially elliptical in general contour.

B is the register, projecting from the face of the door or panel and having a closed front and circular outline.

C is the handle on the front of the register.

What I claim is—

The design for a stove door or panel, substantially as shown and described.

LAZARD KAHN.
